UNITED STATES PATENT OFFICE.

HENRY D. WINTON, OF WELLESLEY HILLS, MASSACHUSETTS.

ELECTRIC SIGNAL.

SPECIFICATION forming part of Letters Patent No. 317,911, dated May 12, 1885.

Application filed July 17, 1884. (No model.)

To all whom it may concern:

Be it known that I, HENRY D. WINTON, a citizen of the United States, residing at Wellesley Hills, in the county of Norfolk and State 5 of Massachusetts, have invented new and useful Improvements in Electric Apparatus for Interlocking Signals, of which the following is a specification.

This invention relates particularly to a system of interlocking signals, such as are generally used on railroad crossings, switches, or draw-bridges, and the object of my invention is to prevent the signal-man from giving a wrong signal.

15 The peculiar devices and combinations which compose my interlocking apparatus are pointed out in the following specification and claims, and illustrated in the accompanying drawings, in which—

20 Figure 1 represents a transverse vertical section of the frame which contains the signal-levers and the mechanism for interlocking the same. Fig. 2 is a longitudinal vertical section of the same in the plane x x , Fig. 1.

25 Fig. 2* is a similar view on a larger scale showing the connections. Fig. 3 is a similar section in the plane y y , Fig. 1. Figs. 4, 5, 6, and 7 are detached views of the electro-magnets and of parts of the interlocking mechanism on a larger scale than the previous figures. Fig. 8 is a side elevation of a semaphoric signal, such as may be used in connection with the signal-levers. Fig. 9 is a diagram illustrating the application of my sys- 30 tem to a railroad-crossing. Fig. 10 is a side view of a double-circuit instrument such as used in my system. Fig. 11 is a plan or top view of the same. Fig. 12 is a plan or top view of an interlocking block signal instrument such as used in my system. Fig. 13 is a side view of the same. Fig. 14 is a side view of a track-circuit-breaking instrument such as may be used in my system. Fig. 15 is a similar view of a track-circuit-closing instru- 35 ment such as may be used in my system. Fig. 16 is an electric signal such as may be used in my system.

40 In the drawings, the letter A designates the box or frame in which is firmly mounted the shaft B. This shaft forms the fulcrum of the signal-levers C C' C'' C''' , which turn loosely thereon, the number of which depends upon

the number of signals which are to be operated by the signal-man in charge. To the lower end of each of the levers is secured an iron 55 piece, D, provided with two arms, d d' , upon one of which is secured a weight, e, while the other connects by a cable or chain with the signal S, Fig. 8. The normal position of this signal is "danger," such position being 60 shown in full lines in Fig. 8. It is kept in that position by the weight e. When the lever C' is moved in the direction of the arrow marked near it in Fig. 1 the signal S is drawn down to the position shown in dotted lines in 65 Fig. 8, (indicating "danger.") and by returning the lever the signal will return to its normal condition, (indicating "danger.") The lever C' may be connected by a system of levers to a switch, so that the switch can be 70 moved by the action of the lever:

With the lever C' is combined a catch-rod, E, the lower end of which catches in front of the stop F, formed on an iron casting, which is secured at one end to the timber G, while 75 its other end rests upon the shaft B. This piece is made to flange on either side of the lever, as shown at F F, Fig. 3, and it forms a hold and guide for the lever, to prevent it from moving upon the shaft in a lateral direction. The catch-rod is retained in its normal condition by a spring, H, and it is provided with a handle, I, which is pivoted to the lever C. By pulling this handle in the direction of the arrow marked near it in Fig. 85 1, the lower end of the catch-rod is raised clear of the stop F, and the lever C can be moved for the purpose of actuating the signal, as already described.

Secured to the lower end of the catch-rod E 90 is an insulating-block, d, on the lower edge of which is a metallic strip, d*. When the catch-rod is in its normal condition, this strip bears upon two springs, e e', Figs. 1 and 2, which are secured to the timber G, and thereby a 95 circuit-closer is formed. When the catch-rod is raised, this circuit is broken. The timbers G G' rest upon a casting, f*, (see Figs. 1 and 2,) and on the timbers G G' are secured plates f f', which form the guides for a sliding bar, 100 K, from the edge of which extends a pin, g, into a slot, g', in the lever C', so that by moving the lever a sliding motion is imparted to the bar K. On the bar are secured two ad-

justable lugs, o o' , Figs. 1 and 5, which govern the distance of its movement. L and M are electro-magnets for locking the bar K .

Fig. 4 is a front view of the locking-magnet L , and Fig. 5 is a side view of the same. L is the electro-magnet, and L' is its armature, which swings in bearings h h' . From the back side of the armature extends an arm carrying an adjustable balance-weight, h^* , which is so adjusted as to require a slight power to raise the armature. A pin, i , projecting from the side of the plate f , forms the back stop of the armature. On the end of the armature is a finger, i' , and when the magnet is devitalized so that the armature falls to the position shown in full lines in Fig. 5 the finger i' drops in front of the bar K and the bar cannot be moved. Whenever the electro-magnet L is devitalized, the bar K is locked and the lever C cannot be pulled from its normal position, and of course the signal connected with the lever cannot be actuated; but when a circuit is passing through the magnet L the bar K is unlocked and the lever C is free to be moved. The magnets M on the opposite or back side of the frame A perform the same operation. If the lever has been pulled, the locking device connected with the electro-magnet M may operate to lock the lever, so that it cannot be returned until such time as the magnet is vitalized. The magnets L therefore may be called the front locks and the magnets M the back locks.

With the sliding bar K are combined circuit-closers t t^* , the operation of which will be understood by referring to Figs. 5, 6, and 7.

Secured to the timbers G G' are brackets t , on which are mounted insulating-blocks t' , which carry the springs t t^* .

On the sliding bar K is secured an insulated cam, K' , having a metallic strip, K'' , on one side, Fig. 7. When the bar K is moved in the direction of the arrow marked on it in Fig. 7, the cam K' comes in contact with the springs t t^* , and a metallic connection is made by the strip K'' , thus closing a circuit. On returning the sliding bar the cam K' comes in contact with the springs t t^* on its insulated side, and no circuit is made. From this description it will be seen that it is impossible to move the lever C unless the catch-rod E is first pulled. This act may break a circuit, as described, and if no current is passing through the front locking-magnets, the lever C cannot be moved, because the bar K is locked. If the lever can be and is pulled, two circuits can be made by the cams K' secured to the bar K , while no circuits are made in returning the lever.

I will now explain how the levers C C^2 C^3 C^4 are interlocked by reference to the circuits indicated by dotted lines in Fig. 2*. By tracing these circuits it will be seen that a circuit is complete from battery X , wire 11, wire 12, circuit-closers e e' on lever C , wire 13, locking-magnet L^2 , wire 14, circuit-closers e e' on levers C^3 , wire 15, locking-magnet L^4 to the

ground. The locking-magnets L^2 and L^4 of levers C^2 C^4 being vitalized, these levers are free to be moved. A circuit is also made from battery X , wires 11 and 17, circuit-closers e e' on lever C^2 , wire 18, locking-magnet L^1 , wire 19, locking-magnet L^3 , wire 20, circuit-closers e e' on lever C^4 , wire 21 to the ground, and consequently levers C C^3 are unlocked. Now, then, if lever C is pulled, the circuit through locking-magnets L^2 L^4 are broken, which locks the corresponding levers, and they cannot be moved until lever C is returned to its normal condition. In the same way, if lever C^2 is pulled it breaks the circuits through locking-magnets L^1 L^3 and the corresponding levers, C C^3 , cannot be moved. By pulling lever C^3 the levers C C^3 are locked. In this combination both the levers C C^3 can be pulled, and then the levers C^2 C^4 cannot be moved until both levers C C^3 have been restored, and vice versa. Other combinations may, however, be made, and when a large number of combinations are required I can introduce relay-instruments into the circuits.

I will now describe the application of my interlocking system to a railroad-crossing, such as illustrated in Fig. 9. In the drawings, the letters R E' R'' R^* represent the tracks of a railroad-crossing, the trains running in the direction of the arrow marked on these tracks. N N' N'' N^* are electric signals placed at suitable distances from the crossing. S S' S'' S^* are semaphores or home-signals, such, for instance, as shown in Fig. 8. T T' T'' T^* are track-circuit-breaking instruments, and t t' t'' t^* are track-circuit-closing instruments. C C^2 C^3 C^4 are levers, such as shown in Figs. 1, 2, and 3, and they connect with the signals S S' S'' S^* by cables, rods, or chains s s' s'' s^* and bell-crank levers or pulleys. e^5 e^6 e^7 e^8 are the circuit-closers, such as shown at e e' , Figs. 1 and 2. L^9 L^{10} L^{11} L^{12} are the front locking-magnets, and M^{13} M^{14} M^{15} M^{16} are the corresponding back locking-magnets. t^1 t^{10} t^{11} t^{12} are the circuit-closers appertaining to the front locking-magnets, (such as marked t'' t^* in Figs. 1, 5, and 6,) and m^{13} m^{14} m^{15} m^{16} are the corresponding circuit-closers belonging to the back locking-magnets. O O^2 O^3 O^4 are interlocking block signal instruments, such as illustrated in Figs. 12 and 13. P P^2 P^3 P^4 are double-circuit instruments, such as shown in Figs. 10 and 11. The normal condition of the electric signals and the semaphores is at "danger." The operator can clear both the distant signal N and the home-signal S by pulling the lever C . By this operation the semaphore S is brought in a position indicating "safety," and at the same time a circuit is made by circuit-closer t^1 from battery Y , wire 31, magnet o on instrument O' , wire 32, magnet o' , wire 33, circuit-closer t^1 , wires 34 and 49 to the ground. This circuit closes spring o^2 on instrument O' , thereby completing a secondary circuit from battery Y , wire 31, wire 35, spring o^2 , wire 36, magnet o^3 , wire 37, a closed spring in track-

instrument T, the electro-magnet of signal N, wire 38 to the ground, thereby raising the signal N to "safety" and locking the spring o^2 , as hereinafter explained. The act of pulling the 5 lever C' breaks the circuit at circuit-closer e^5 , which runs through locking-magnets L¹⁰ and L¹², and the corresponding levers, C² and C⁴, become locked, so that it is impossible to operate the signals N' N* and S' S*. There is 10 no objection to pulling lever C³, as a train may be allowed to cross on track R. If lever C³ is pulled it becomes impossible to operate levers C² C⁴ until both levers C' C³ are restored again, as already explained. The train which 15 has been given the right of way proceeds, and on reaching the track-instrument T it breaks the circuit of signal N and this signal falls to "danger" at the same time the circuit to "danger" at the same time the circuit 20 through locking-magnet o^3 is broken and spring o^2 is opened. After pulling lever C' it is desirable to lock it back so that the operator cannot restore it before the train has passed the crossing. This is accomplished by the 25 back-locks in the following manner: A circuit is complete from battery Z, wires 41 and 42, spring p on instrument P', wire 43, back locking-magnet M¹³, wires 44 and 45 to the ground, and thus the lever C' is normally 30 unlocked on the back side; but when the lever is pulled a circuit is made by circuit-closers m^{13} from battery Z, wire 41, wire 46, magnet p' on instrument P', wire 47, circuit-closer m^{13} , wires 48 and 49 to the ground, spring p on instrument P' is opened, the circuit 35 through the back locking-magnet M¹³ is broken and its armature falls, so as to lock the bar K, Figs. 1 and 5, of lever C' on the back side. The lever C' therefore cannot be restored to its normal condition until a circuit is closed 40 through magnet M¹³, which is accomplished by the action of the train on the track-instrument t. By this action a circuit is closed from battery Z, wire 41, wire 50, magnet p' on instrument P', wire 51, circuit-closer on the 45 track-instrument t, wire 52 to the ground. By this circuit the spring p on instrument P' is closed again and locked, the circuit through locking-magnet M¹³ is completed and lever C' is unlocked on its back side, so that it can be 50 restored to its normal condition.

In place of the semaphores S S' S'' S*, derailing-switches may be used, which are connected to the levers C' C² C³ C⁴ by connections similar to those shown for connecting the semaphores with the levers. The normal condition 55 of these derailing-switches is such as to carry a train off the main line. When it is desired to give the right of way to a train on the track A', for instance, the switch which takes the 60 place of the semaphore S will be thrown on the main line—that is to say, in such a position that the main line is complete. This act will make it impossible to move the switches on the conflicting tracks, so that, if an engineer 65 disobeys his signal, his engine will be thrown from the track instead of crossing in the face of a train which has the right of way.

What are here termed "derailing-switches" are not to be understood as switches or obstructions which throw the train entirely off the track, but only such as derail it so far as the main track is concerned, and switch or shunt such train onto a siding, switch, or shunt, which may be of any desired length, such length, for instance, as guarantees safety 75 to the train derailed, so far as concerns the main track, and leaves the main track free for such train as has the right of way.

The double-circuit instruments P' P² P³ P⁴ are constructed as shown in Figs. 10 and 11. 80 In these figures the letter p^2 designates the main magnet, the armature p^3 of which is secured to a lever, p^4 , which connects by a rod, p^5 , with a lever, p^6 . This lever has its fulcrum in center points, p^7 , and its lower end connects with a rod, p^8 , which carries a roller-stud, p^9 . If the main magnet is vitalized and its armature is attracted, the roller-stud p^9 closes the spring p . In this position the armature p^3 of the main magnet is locked by the armature-lever p^{10} of the releasing-magnet p' . If this releasing-magnet is vitalized, its armature-lever releases the armature-lever of the main magnet, the armature p^3 falls back, and the spring p is opened. 95

The interlocking block signal instruments O' O² O³ O⁴ are constructed as shown in Figs. 12 and 13.

The letter o' designates the main magnet. o^3 is the locking-magnet, and o the additional 100 magnet. The armature o^4 is secured to a lever, o^5 , which connects by a rod, o^6 , with a lever, o^7 , the lower end of which is pivoted to a rod, o^8 , that carries a roller-stud, o^9 . When the main magnet is vitalized, the roller-stud 105 acts upon the spring o^2 and closes the same. If at the same time a circuit is closed through the locking-magnet o^3 , the armature-lever o^{10} of this magnet locks the armature-lever o^5 of the main magnet, and the spring o^2 remains 110 closed until the circuit through the locking-magnet is broken.

The track-instruments T, which I use, may be constructed as shown in Fig. 14. The springs r r' are closed in their normal condition, and if the lever r^2 is depressed by the wheels of a passing train, the springs r r' are opened and the circuit previously closed through them is broken. In the track-instruments t, Fig. 15, the springs r^3 r^4 are normally 120 open, and they are closed by the action of the wheels of a passing train upon the lever.

The electric signals N may be of any well-known construction, such, for instance, as shown in Fig. 16. When the signal-magnet 125 u is vitalized, the signal-disk is raised out of sight, or to a position of "safety." If the signal-magnet is devitalized, the signal-disk drops in sight, indicating "danger."

I make no claim for the broad idea or method 130 of controlling railway-signals from a distance by making or breaking by means of electricity the connection between a semaphoric signal and a hand-lever employed to move it, so that

the said lever can be rendered operative or inoperative on the signal, and that when it is so rendered inoperative the signal is moved to or kept at its danger attitude.

5. What I claim as new, and desire to secure by Letters Patent, is—

1. In an electrically-operated railway-signal, the combination of the hand-lever C' , the sliding catch-rod E , having an insulating-strip, 10 d , and contact-piece, d^* , the circuit-closing spring e , and an armature and magnet, electrical connectors, and a sliding bar, K , for locking the hand-lever, with a semaphoric or other signal connected with the lever C' , and a frame having a catch device for the rod E , substantially as described.

2. The combination, with two levers, $C' C^2$, and with the connections of these levers with semaphores or switches, of catch-rod, one for 20 each lever, the contact-pieces attached to these catch-rod, the circuit-closing springs for each contact-piece, the sliding bars, one for each lever, the locking-magnets, and the connections of the locking-magnets and circuit-closers with a battery, substantially as and for the purpose described.

3. The combination, substantially as hereinbefore described, with the lever C' and with the connections of this lever with a semaphore 30 or switch, of the sliding bar K , the connections substantially such as herein described between this bar and the lever, the front locking-magnet L' and the back locking-magnet M .

4. The combination, with two levers, $C' 35 C^2$, and with the connections of these levers with semaphores or switches, of catch-rod, one for each lever, the contact-pieces attached

to these catch-rod, the circuit-closing springs for each contact-piece, the sliding bars, one for each lever, the circuit-closing springs acted 40 upon by these sliding bars, the front locking-magnets, the back locking-magnets, and the connections of these magnets, and of the circuit-closing springs with a battery or batteries, substantially as and for the purpose shown 45 and described.

5. The combination, substantially as hereinbefore described, with two railroad tracks, $R' R^*$, which cross each other, of two levers, $C' C^2$, connected to semaphores or derailing-switches, means substantially such as herein described for interlocking the levers, track-instruments $t t'$, double-circuit instruments, $P' P^2$, and the connections of these parts with 50 a battery or batteries.

6. The combination, substantially as hereinbefore described, with two railroad-tracks, $R' R^*$, which cross each other, of two interlocking levers, $C' C^2$, connected to two semaphores or derailing-switches, means substantially such as herein described for interlocking the levers, track-instruments $t t'$, double-circuit instruments $P' P^2$, electric signals $N N'$, track-instruments $T T'$, interlocking block signal instruments $O' O^2$, and the connection 60 of these parts with a battery or batteries.

In testimony whereof I have hereunto set my hand and seal in the presence of two subscribing witnesses.

HENRY D. WINTON. [L. S.]
